UNITED STATES PATENT OFFICE.

GEORGE M. RODNER, OF MINNEAPOLIS, MINNESOTA.

ADDRESSING MACHINE.

Application filed August 28, 1922. Serial No. 584,698.

This invention relates to an addressing machine, and particularly to such a machine of the type using stencil cards carrying the address or other matter which it is desired 5 to print. While such machines are now greatly used the same are quite expensive and comprise complicated mechanisms. There is a great market and a demand for a simple and inexpensive machine which can 10 be purchased and used by many organizations of limited means.

It is an object of this invention, therefore, to provide an addressing machine of simple and inexpensive construction which will efficiently and rapidly print the desired addresses or other matter.

It is a further object of the invention to provide such a machine comprising an inking roller and a reciprocating plunger co-operating therewith having means for holding the plunger in firm engagement with the roller during the printing operation.

It is another object of the invention to provide such a machine having a vertically reciprocating plunger co-operating with the inking roller.

It is still another object of the invention to provide an ink containing casing in the upper portion of which the ink roller is 30 journaled and to provide an ink supplying and stirring roller in contact with said roller and journaled beneath the same in said casing.

It is a further object of the invention to provide an inking roller and a printing means co-operating therewith, together with a guideway along which the stencil cards move into position between said roller and printing means and to have resilient means 40 on said guideway in alinement with the roller for elevating the cards slightly as they come into said position.

It is still another object of the invention to provide the inking roller with a blade 45 extending over and across the surface thereof for removing and distributing ink thereon, which blade is adjustably and resiliently held in contact with said roller and is so constructed that the inclination thereof 50 may be varied.

These and other objects and advantages of the invention will be fully set forth in the following description made in connection with the accompanying drawings in 55 which like reference characters refer to the

same parts throughout the different views, and in which,

Fig. 1 is a view in side elevation of the machine;

Fig. 2 is a top plan view thereof;

Fig. 3 is a vertical section thereof taken substantially on the line 3-3 of Fig. 1, shown on an enlarged scale;

Fig. 4 is a vertical section taken on the line 4-4 of Fig. 2 as indicated by the 65 arrows, also shown on an enlarged scale;

Fig. 5 is a central longitudinal section of the upper part of the machine;

Fig. 6 is a view in side elevation partly in section of the inking devices in the machine, shown on an enlarged scale;

Fig. 7 is an enlarged view in vertical section of the driving mechanism of the machine;

Fig. 8 is a vertical section taken on the 75 line 8-8 of Fig. 7;

Fig. 9 is a partial view of the mechanism for moving the card-supporting means in the delivery magazine shown on an enlarged scale;

Fig. 10 is a view as seen from the right of Fig. 9;

Fig. 11 is a vertical section on an enlarged scale taken on the line 11-11 on Fig. 1, as indicated by the arrows;

Fig. 12 is an enlarged view in front elevation of the lower end of the printing plunger; and

Fig. 13 is a vertical section taken on the line 13-13 of Fig. 12.

Referring to the drawings, the machine comprises a frame of simple construction comprising four spaced leg members 1 bent outwardly at their lower ends to form a firm supporting base having suitable cross brace members adjacent the top thereof and supporting at their upper ends a frame plate 2. A pair of spaced strips 3 shown as of rectangular cross section extend longitudinally of the plate 2 and strips 4 are bolted to said members 3 and the plate 2 and extend inwardly from the former to form a guideway. The members 3 have a thin lip extending inwardly therefrom to form the bottom of the guideway and a stencil card feeding plate 5 is adapted to reciprocate in contact therewith and a reciprocating plate 6 overlies the plate 5 and also reciprocates in said guideway having its sides extending under the plate or strips 4. The plate 6 110

has lugs extending upwardly at each side thereof and headed studs 7 are secured therein and form the pivots for the links 8 through which movement is imparted to the member 6. The member 6 has pivoted thereto substantially centrally thereof an angularly formed lever member 9 provided with a knurled or other suitable handle 10. The lever 9 has a pin 11 projecting over the member 6 disposed under the cross bar 12 connecting a pair of vertical pins 13 disposed in vertical bores extending through the member 6 and adapted to pass into spaced holes in the plate 5. A spring 14 is normally under tension tending to pull the pins 13 downwardly into engagement with plate 5. When the lever is swung, as shown in Fig. 3, the pin 11 raises the pins 13 out of engagement with the plate 5, but if the lever is swung to the opposite side said pins are then moved into engagement with said plate by the spring 14. The plate 6 has a projection extending downwardly through a slot 15 formed in the plate 5 and through a slot 16 formed in the plate 2, which projection is adapted to be connected to a pair of links 17 and 18 for a purpose to be later described.

A stencil card containing magazine 19 is mounted on the frame and adapted to receive an extension magazine 20 in which the stencil cards A are disposed. The cards are moved downwardly through said magazine by a weight member 21 placed on the top thereof shaped to fit in said magazine and provided with a suitable handle on its upper side. The plate 2 has other spaced strips 22 secured thereto and extending longitudinally thereof adapted to form a guideway for the stencil cards A, the bottom of which guideway is in alinement with the bottom of the guideway formed by the members 3 and 4, so that the lowermost card in the magazine 19 may be pushed forwardly in said guideway formed by the strips 22 by the forward movement of the feeding plate 5, the card then being pushed further along the guideway by the next succeeding card moved by the member 5.

The plate 2 is provided adjacent its forward end with an opening 23 and an inking roller 24 is journaled in an ink-containing casing or receptacle 25 secured to the underside of the plate 2, so that its top surface projects slightly through said opening, the uppermost point of said roller 24 being slightly above the bottom of the guideway formed by member 22. A printing plunger 26 is mounted for vertical movement and guided in a head formed on bracket 27, which bracket extends rearwardly and is bolted to the front of the magazine 19. The lower end of plunger 26 is formed as a transversely extending plate and a plate 27 having a lower concave surface when in en-

gagement with roller 24 concentric with the axis thereof is supported by said plate and plunger by spaced screws 28 projecting upwardly therefrom and through holes formed in said plunger plate, said screws being provided with suitable nuts for varying the vertical position of member 27, said member being firmly held in position by the adjustable screws 29 disposed at each side of the plunger plate and contacting the member 27 at their lower ends. Said member 27 is covered on its undersurface with a layer 30 of soft rubber or similar material. The plunger 26 has a slot extending through its upper end traversed by a pin 31 and a swinging arm 32 has its front end disposed in said slot, which end is also provided with a slot receiving the pin 31. The lever 32 is loosely and swingingly mounted at its rear end on a shaft 33 extending across the front of the magazine frame 19 and supported in spaced bearings projecting therefrom. The hub of the arm 32 has a tooth 32a extending at one side thereof adapted to be engaged by a similarly formed recess in a collar-like member 34 splined to the shaft 33 and urged toward the member 32 by a coiled spring 35 disposed between the member 34 and one of the bearings for the shaft 33. The member 34 is provided with a projecting fingerpiece 36 by which the same can be moved against the pressure of spring 35 out of engagement with member 32. The shaft 33 has arms 37 secured at each end thereof, which arms depend and are pivoted at their ends to the links 8 already described. One end of the shaft 33 projects beyond the arms 37 and has secured thereto an arm 38 extending downwardly and rearwardly therefrom and pivotally connected to a fork member 39 to the other end of which is connected a bent link 40 adapted to be connected to the driving mechanism to be later described.

The inking roll 24 is arranged for intermittent rotation and for this purpose the journal or bearing shaft therefor is provided at one end with a ratchet wheel 41 adapted to be engaged by a pawl 42 pivoted to an arm 43 having a projection connected to a coiled spring 44 also connected to the link 43 and so disposed as to move the pawl 43 toward the teeth of the ratchet wheel 41. The lever 43 is pivoted to the shaft of the roller 24 and is provided at its other end with a plurality of holes to any one of which a link 17, already described, is adapted to be connected by a suitable pivot stud. It will thus be seen that as the link 17 is reciprocated by member 6, that the roller 24 will be intermittently rotated as indicated by the arrow in Fig. 6. Mounted below the roller 24 and urged into frictional engagement therewith by a coiled spring 45 is another roller 46 journaled upon a shaft 120

provided with heads 47 at each end surrounding the vertical rods 48, the springs 45 being disposed between said heads and a collar 49 pinned to the lower end of the rod 48. The roller 24 has a blade 50 overlying and engaging the surface thereof at one side, which blade is carried in an arm pivotally mounted on a shaft 51, which shaft is mounted in bearing members 52 supported from the top of plate 2 by screws 53 having a suitable turning edge thereon. The shaft 51 is further provided with an arm or lever 54 bent into right-angular shape and having its end extending downwardly and provided with a stud for connecting the same to a coiled tension spring 55, the other end of which is connected to a suitable handled screw 56 threaded through a bracket arm 57 depending from the under-surface of the plate 2. It will be readily seen that by turning the screw 53 the vertical position of shaft 51 will be varied as will also the inclination of the blade 50 and that by turning the screw 56 the tension of spring 55 and the pressure of the blade against the roller 24 will be varied and receptacle 25 is supported and clamped to members 58 carried by depending rods 59 secured at their upper ends to the bottom surface of plate 2.

A magazine 60 is disposed at the front end of the machine and bolted, or otherwise, secured to the front edge of plate 2. This magazine comprises a vertically extended casing of substantially rectangular shape, the front portion of which is open, and a supporting plate 61 adapted to support the stencil cards A is adapted to move vertically in said magazine. The plate 61 has a laterally projecting arm from which an arm projects toward the machine carrying a hub forming a nut adapted to embrace and travel on a bolt 62 mounted in suitable brackets 63 bolted to a vertically extending angle-shaped member 64 which is, in turn, bolted to the front of the machine frame, the magazine 60 fitting in the corner of said member. Mounted in the brackets 63 is a beveled gear 65 meshing with a pinion 66 adapted to turn loosely on the upper end of screw 62. The upper end of said screw is formed of reduced diameter and has secured thereto a ratchet wheel 67 with the teeth of which pawl 68 pivoted on the top of pinion 66 is adapted to engage, said pawl being urged toward said teeth by a spring (not shown). The outside of the gear 65 has secured thereto a downwardly projecting arm 69 having adjacent its lower end a plurality of holes, to any one of which the link 18 is adapted to be connected by a suitable headed nut. It will thus be seen that, as the link 18 is reciprocated by member 6, that the gear 65 and pinion 66 will be intermittently rotated and that the pawl

68 will thus give intermittent rotations to the screw 62, which rotations will, in turn, move the supporting plate 61 downwardly. Said plate 61 is yieldingly held in position by a spring 70 carried by an arm 71 projecting from the bracket 63, which arm can be moved to allow the member 61 to be swung out of the magazine 60. The sides of the magazine 60 are provided with sleeves 72 extending vertically at the front corners thereof and resilient rods 73 are journaled therein and have their lower ends projecting diagonally inwardly in said magazine, said rods being formed with looped portions 74 intermediate, their length lying along the sides of the magazine 60. The magazine 60 is adapted to be bodily removed from the machine and when the plate 61 is swung out of the same the lower ends of the rods 73 will support the stencil cards A, said rods can be moved, however, by manipulation of their portion 74 to swing their lower ends out of the line of the magazine and the cards can thus be discharged through the lower end thereof.

The machine is provided with a stub shaft 75 on which is journaled a belt pulley 76 adapted to be driven from a suitable source of power. Said stub shaft is supported in a suitable bracket 77 bolted to the legs 1. The pulley 76 has circumferentially spaced pins 78 projecting from one side of its hub adapted to engage a pin 79 projecting from the extended hub of an eccentric bearing member 80 supported on shaft 75. The pin 79 has a reduced central portion and is received in a recess 81 in hub 80 and urged outwardly of said recess by a coiled compression spring 82. The hub 80 carrying the pin 79 is provided with an annular groove 83 which extends into the recess 81, and a lever 84 pivoted adjacent the top of the frame is provided with a knife edge or wedge surface 85 adapted to contact with the beveled shoulder at the inner side of the reduced portion of pin 79 when said lever is moved into the groove 83 to force said pin into the recess 81 so that the same is out of alignment with the pins 78. The lever 84 is normally urged into said groove 83 by a spring 94 secured to its lower end and to one of the legs 1. In this normal position of the lever the pulley 76 is disconnected from the crank hub 80. A treadle lever 86 is pivoted to the rear of the frame and has an upwardly and forwardly projecting arm 87 adapted to contact with the lower end of lever 84 and move the same out of the groove 83. The pin 79 is then urged outwardly by the spring 82 and contacted by one of the pins 78 and the crank hub 80 thus turned. The crank hub 80 is provided with a headed and nutted stud 88 formed to pivot for the lower end of link 40.

From the structure described, it will be

seen that rotation of the crank 80 through link 40 and through arms 38 and 32 will move plunger 26 downwardly in contact with the roller 24. The rollers 24 and 25 are made with wooden core and a covering of soft rubber or similar material. As the plunger is pressed down, the soft material of the roller and the soft material 30 on the plunger tend to push the plunger upwardly and in order to hold the same firmly in engagement with the roll while the crank pin 88 on crank 80 swings across its dead center position, a brake strap 89 is provided carrying a brake block 90, both of which engage with the outer portion of the hub of crank 80. The strap 89 is provided with a screw 91 engaging the block 90 in order to vary the position thereof and the pressure of the same against the hub of the crank 80. The said outer portion of said hub is provided with a raised portion 92 at one part of its periphery and the parts are so adjusted that this raised portion comes in contact with the block 90 when the crank is at that portion of its travel in which the plunger 26 is in engagement with the roller 24. The portion 92 and the brake block 90 thus place a brake or retarding action on the movement of said plunger and prevent any vertical movement thereof in consequence of the reaction of the soft rubber surfaces and thus prevent said surfaces from "kicking back", so to speak, against the crank 90.

The plate 2 is provided with small curved plate springs 93 adjacent the member 22, said spring being in transverse alinement with the roller 24 and curved substantially concentric with the axis thereof.

In the operation of the machine the stencil cards A will be placed in the magazine 19 and 20 and when it is desired to start the machine the treadle 86 will be depressed, thus turning the crank 80, as described, to reciprocate link 40, which, through the arms 37, 38 and links 8, reciprocates the member 6. If the lever 9 is now thrown to connect the plates 5 and 6, the stencil cards A will be fed forward in the guideways and will come into position between the plunger 26 and roller 24, the parts being so adjusted that the card is properly so positioned. Plate 6 has on its upper surface small spaced ribs 6^a having wedge shaped front ends, which pass between the lowermost card and the adjacent card. The latter card is then raised somewhat, friction on the lower card relieved, and the cards prevented from catching on each other and being improperly fed. As the card moves into position, the edges thereof ride up on the springs 93 so that the card is not dragged across the ink surface of roller 24. The sheet to be printed is placed under the plunger 26 and as the same is reciprocated against the roller the printing impression is made. The cards A

are pushed on past the plunger 26 and drop into the magazine 60. Through the reciprocation of link 18 by the member 6, the supporting plate 61 for said cards is successively lowered substantially the amount of the thickness of one of said cards so that the same are gradually piled in said magazine. By means of the brake mechanism comprising parts 89 to 92, the plunger is held down firmly on the roll 24, and will be raised slowly therefrom so that a firm and clear print impression will be made. As the roll 24 is intermittently turned by the reciprocation of link 17 through the mechanism described a fresh surface is brought into play for each one of the stencil cards. As roll 24 is thus turned the roll 46 is also turned and the latter roll being partly submerged in the ink carried in casing 25 supplying the ink to the roller 24 and also acts to stir the ink and keep the same in proper condition. As the surface of roller 24 moves upwardly from roller 46 to printing position, any surplus ink thereon will be removed or efficiently distributed thereon by the blade 50 so that the surface of said roller is properly uniformly inked in the printing operation. The deep tank 25 used to carry the ink prevents any splashing out or spilling of ink during any movement or transportation of the machine about the office in which it may be used. By the structure of the driving mechanism described, if the foot is raised from the pedal lever 86 after the same is depressed, the crank 80 will make but one revolution and the plunger 26 will be depressed but once and only one card printed. If it should be desired to prevent the descent of the plunger 26 without removing the foot from pedal lever 86, the member 34 can be moved to one side by pressing on finger-piece 36. Arms 32 is thus disconnected from the shaft 33 and no movement of the plunger will be made. The various adjustments described, such as that for varying the pressure of blade 50 on roll 24 and the inclination of said blade as well as the speed at which the plate 61 is moved and the amount of movement of roller 24 can be easily and instantly made when desired. The plate 27, at the end of the plunger 26, can also be easily and quickly adjusted when desired.

From the above description it is seen that applicant has provided a very simple and efficient addressing machine and one which can be inexpensively made and will fill a great demand of a great many of the smaller banks and similar institutions which cannot afford to buy an expensive card addressing machines such as now on the market but can afford a machine such as disclosed herein.

It will, of course, be understood that various changes may be made in the form, details and arrangement of the parts with-

out departing from the scope of applicant's invention, which, generally stated, consists in the matter shown and described and set forth in the appended claims.

5. What is claimed is:

1. An addressing machine having in combination a table, an intermittently rotatable inking roller beneath said table having a fixed axis, a means for positioning a stencil card in said table over said roller, and means above said table for pressing said card downwardly against said roller.

10. 2. The structure set forth in claim 1, said plunger having a pin extending transversely thereof adjacent its upper end, a swinging arm pivoted at one end to the machine frame having a slot receiving said pin, and means for swinging said arm about its pivot to reciprocate said plunger.

15. 3. An addressing machine having in combination a frame, a vertically reciprocating plunger therein, a pivot shaft on said frame extending transversely of said plunger, a swinging arm mounted on said shaft engaging said plunger at one end to move the same, a second arm secured to said shaft, a power shaft supported by said frame, a crank thereon and a link connecting said crank and said second arm.

20. 4. An addressing machine having in combination, a frame, a vertically reciprocating printing plunger mounted thereon, a shaft mounted on said frame extending transversely of said plunger, a swinging arm loosely mounted on said shaft and engaging said plunger at its other end to move the same, a spring pressed member splined to said shaft having means thereon engaging said swinging arm to move the same but being movable away from said arm to release the same and prevent movement of said plunger.

25. 5. An addressing machine having in combination, a printing plunger mounted for vertical reciprocating movement therein, a member having a concave undersurface carried by the lower end of said plunger, and means for varying the vertical position of said member.

30. 6. The structure set forth in claim 5, said member having a layer of yielding material on its under concave surface.

35. 7. An addressing machine having in combination, an inking roller, a guideway extending over said roller through which stencil cards are adapted to be moved, a plunger for vertical reciprocating movement over said roller, a member having its bottom surface concave and concentric with the axis of said roller carried by said plunger, and means for varying the distance of said member from the end of said plunger.

40. 8. An addressing machine having in combination, a yielding inking roller, a plunger

mounted for vertical movement over the same, power means for reciprocating said plunger to press the same against said roller, and means for retarding the movement of said plunger as it moves to and from engagement with said roller.

45. 9. An addressing machine having in combination, a frame, an inking roller mounted therein, a plunger mounted for vertical movement above said inking roller, one of said latter members having a resilient surface, a power shaft mounted in said frame, articulated connections between said shaft and said plunger for reciprocating the latter, and a brake mechanism for said power shaft adapted to be applied thereto as the plunger moves against and away from said inking roller.

50. 10. An addressing machine having in combination, a casing, an inking roller comprising a rigid core and a yielding covering thereon journaled therein, means for positioning the stencil over said roller, an ink supply roller journaled beneath said roller and constantly in contact therewith, and means for regulating the film of ink on said inking roller.

55. 11. An addressing machine having in combination a table adapted to have a stencil positioned therein, a casing below said table, an inking roller having a resilient surface journaled therein having its upper surface substantially flush with the top of said table, an ink distributing blade resiliently held in contact with said roller, and means for varying the pressure of said blade against said roller, and an ink supply roller journaled beneath said inking roller and running in contact therewith and with ink in said casing.

60. 12. An addressing machine having in combination, a frame, an inking roller journaled therein, a printing plunger mounted for vertical movement above said roller, a guideway for stencil cards extending between said roller and plunger, a magazine for cards extending above said guideway, means for pressing cards down in said magazine into said guideway, means for moving said cards along said guideway into position between said plunger and roller, a magazine at the end of the said guideway extending below the same, a supporting means for cards therein, and means operated by said second mentioned means to intermittently lower said supporting means.

65. 13. An addressing machine having in combination, an inking roller, a printing plunger mounted for vertical movement thereabove, a guideway for guiding stencil cards into position between said roller and said plunger, and means to slightly elevate said cards as the same move into position above said roller to prevent said cards contacting said roller.

14. The structure set forth in claim 13, said means comprising plate springs curved substantially concentrically with said roller at each side of said guideway.
15. An addressing machine having in combination, an inking roller, a vertically reciprocating plunger constantly positioned above the same, a guideway for guiding stencil cards into position between said roller and plunger, means for moving said cards along said guideway, means for intermittently rotating said roller operated by said last named means and means for supporting material to be printed above said roller.
16. An addressing machine having in combination, a table adapted to have a stencil card positioned therein and adapted to support the material to be printed, bodily stationary means disposed below said table for supplying ink to said stencil, and a pressure means above said table for pressing the material to be printed against said stencil.
17. An addressing machine having in combination, a table, an inking roller in fixed position beneath said table, means for positioning a stencil card in said table over and slightly spaced from said roller, and means above said table for pressing said card downwardly against said roller.
18. An addressing machine having in combination, a table adapted to have a stencil card positioned therein, a plunger above said table for pressing material to be printed against said card, means for reciprocating said plunger, and means for rendering said reciprocating means inoperative.
19. The structure set forth in claim 1, said plunger having a yielding lower surface, the said roller having a rigid core and a layer of yielding material thereon.
20. An addressing machine having in combination, a table, an inking roller beneath said table, means for positioning a stencil card in said table over and slightly spaced from said roller, and means above said table for pressing said card downwardly against said roller, said roller forming the support against which said stencil card is pressed.

In testimony whereof I affix my signature.

GEORGE M. RODNER.
